UNITED STATES PATENT OFFICE.

KARL A. STRITTER, OF NAHANT, MASSACHUSETTS.

SEWING-MACHINE.

1,212,841.

Specification of Letters Patent. Patented Jan. 16, 1917.

Application filed December 30, 1914. Serial No. 879,642.

To all whom it may concern:

Be it known that I, KARL A. STRITTER, a citizen of the United States, residing at Nahant, in the county of Essex and State 5 of Massachusetts, have invented certain new and useful Improvements in Sewing-Machines, of which the following is a specification.

My invention relates to sole sewing machines and it has for its object to provide an improved machine of this kind that is particularly adapted to be used to sew the bottom welt strip to the tread side of the sole of the improved rubber-soled boot or 15 shoe shown and described in my application for Letters Patent of the United States filed December 8, 1914, Serial No. 876053.

The present invention consists, broadly, of a sole sewing machine having means for 20 directing a welt strip into position onto the tread side of the sole of a boot or shoe and into the path of the needle so that said welt strip receives the sole attaching stitches and is sewed to the tread side of 25 the sole at the same time that the sole is sewed to the upper part of the shoe.

In the preferred form of my invention the presser foot of the sole-sewing machine is constructed to serve also as a welt-strip 30 guide by means of which the tread welt strip or the like is guided into position on the margin on the sole and into the stitching line as the operation of sewing the sole progresses, the said presser-foot guide serving, together with the manipulation of the shoe by the operator, to bend the tread welt sidewise without buckling as the sewing proceeds around the bends or curves, particularly while traveling around the toe.

40 Other features of my invention are hereinafter pointed out.

In the accompanying drawings:—Figure 1 is a front elevation of a sole sewing machine embodying one form of my invention. 45 Fig. 2 is a front elevation of the presser foot of the sewing machine shown in Fig. 1. Fig. 3 is a side view of the presser-foot. Fig. 4 is a top plan view of the presser-foot. Fig. 5 is a bottom plan view of the 50 presser-foot. Fig. 6 is a detail partly in section. Fig. 7 is a detail described later. Fig. 8 shows a modification.

Herein I have shown my invention as embodied in a machine for sewing soles to

welts but, as will be clear later, the invention may be embodied in other types of sole sewing machines.

Having reference to the drawings, A represents the work rest or table, B the awl, C the needle, D the shuttle, E the looper 60 and F the presser foot. The presser foot F comprises a shank f fastened as usual to the presser foot lever f' by screws, and a foot, proper, f² made with a needle and awl slot f³ which provides two arms or 65 tines f⁴ and f⁵ adapted to rest upon the work at each side of the stitching line and at each side of the point of perforation of the awl. On its under face the presser foot is made with a longitudinal recess f⁶ bordered upon its rear side by a relatively deep longitudinal shoulder f⁷ and upon its front side by a relatively shallow longitudinal shoulder f⁸. Adjacent the inner end of slot 70 f³ and upon the under side of the presser foot is a guide fin or boss f⁹ located about midway between the shoulders f⁷ and f⁸. At its advance end the presser foot is made with an upwardly oblique guide tube or 75 passage f¹⁰ whose lower end is at one end 80 of the recess f⁶.

The presser foot just described is for use with a welt strip G made as shown in Fig. 7 and the end of said strip is threaded down through the passage f¹⁰ with its lower end 85 occupying the recess f⁶ and held in the paths of the needle and awl by the shoulders f⁷ and f⁸. The top side of welt strip G may be formed as shown with a longitudinal groove g the purpose of which will 90 presently appear. When the welt strip is threaded down through the presser foot the fin f⁹ occupies the groove g and thereby assists the shoulders f⁷ and f⁸ in holding the strip against lateral displacement thus insuring its proper presentation to the needle and awl.

When the machine is in operation sewing the rubber sole, shown at H in Fig. 6, to the usual upper welt J, the awl and 100 needle both pass through welt G as well as sole H and upper welt J so that the stitches pass through and bind all three of these parts together, the welt G being guided down onto the sole into the path 105 of the stitches by passage f¹⁰, shoulders f⁷ and f⁸ and fin f⁹. Upon the occasion of each penetrating stroke of the awl B the

welt G is held against buckling or rising under the thrust of the awl by the arms or tines f^4 and f^5 at each side of the awl.

The sole H may be made upon its tread side with a marginal recess g' within which the strip G is laid by the welt guiding presser foot F whose up and down movements combined with the feed of the work serve to force or crowd the welt strip accurately and fully into the recess g' . This is important and desirable particularly where the welt strip G and its recess g' are treated with cement before the strip is applied to the sole. It is desirable to make the arms or tines f^4 and f^5 at least as long as the distance between two stitches produced under the maximum feed stroke of the awl so that each time the presser foot descends onto the work for a new stitch the two arms or tines not only hold the welt strip G down onto the sole at each side of the awl while the latter is passing through the work but also at the same time press and hold down the material of strip G at each side of the preceding stitch, thereby maintaining intimate contact at that point and practically subjecting all parts of the strip G to pressure from the presser foot for a period of time equal at least to the time required to make two stitches.

In sewing around sharp inward turns as, for example, the toe the welt strip G tends to draw out sidewise from under the presser foot as it leaves the latter and ordinarily the shoulder f^4 will oppose this and serve to hold the strip against displacement relatively to the needle and awl while making such turns, but the engagement of the fin f^9 with the groove g of welt G further insures against displacement of the welt strip relatively to the needle and awl and also causes the stitches to follow and occupy the groove. In making an *ort* turn as when sewing from the shank to the ball of the sole, the shoulder f^6 , assisted by fin f^9 maintains the welt

strip in proper position relatively to the needle and awl.

The form of presser foot shown in Fig. 8 is intended for stiff and comparatively heavy welt strips G cut from full grain leather and is characterized by having its recess f^8 and passage f^{10} curved in the same direction as an inward turn on the sole as at the toe. This curved shape of the presser foot acts to impart a curved shape to the welt strip as it is delivered to the needle and awl and materially assists in properly negotiating sharp inward turns.

In order that the welt strip G will be delivered onto the sole H in an exact and definite position relatively to the work table or rest A so that it will properly fit into the recess g' , the work rest by which the shoe is guided during the sewing operation, should be accurately positioned relatively to recess f^8 .

What I claim is:—

In a sewing machine for attaching outer-soles, in combination, a shoe guiding work rest; a single needle; a presser foot, a welt guide constructed with means for guiding a grooved welt strip into position on the tread side of the outer sole, said guiding means including a guide tube leading toward the needle and a projection on the work-engaging face of the presser foot located wholly and immediately between the delivery end of said tube and said needle for engaging the groove of the welt strip to guide the latter into the path of the needle as it leaves said tube so that said welt strip receives the sole attaching stitches and is sewed to the sole at the same time that the sole is sewed to the upper portion of the shoe.

In testimony whereof I have affixed my signature, in presence of two witnesses.

KARL A. STRITTER.
